UNITED STATES PATENT OFFICE.

JOHN T. MEATS, OF TAUNTON, MASSACHUSETTS.

SUPPORT FOR SPINNING-SPINDLES.

SPECIFICATION forming part of Letters Patent No. 394,200, dated December 11, 1888.

Application filed July 5, 1888. Serial No. 279,084. (No model.)

To all whom it may concern:

Be it known that I, JOHN T. MEATS, of Taunton, county of Bristol, State of Massachusetts, have invented an Improvement in 5 Supports for Spinning-Spindles, of which the following description, in connection with the accompanying drawings, is a specification, like letters on the drawings representing like parts.

10 This invention has for its object to improve the construction of spindle supports or bearings to insure steady running.

In my invention the bearing-tube, surrounded by an outer case or holder, is provided with a lug which rests upon a spring sustained in a recess in the outer case, the said spring, besides supporting the spindle in a yielding manner, being also shown as aiding in preventing the rotation of the bearing-tube 20 in the outer case, and hence I denominate the spring as a "supporting" and "locking" spring.

My invention consists, essentially, in the combination, with an outer case having a recess at one side and a holder and a spring placed in the said recess, of a bearing-tube having a projecting lug to enter the said recess and rest on the said spring and sustain the said tube, substantially as will be described.

Other features of my invention will be hereinafter described, and pointed out in the claims at the end of this specification.

Figure 1 in vertical section shows a spindle bearing or support embodying my invention, the spindle being in elevation. Fig. 2 is a section below the dotted line x , Fig. 1. Fig. 3 is a detail in vertical section of the upper end of the outer case or holder with the spring therein and the surrounding collar, the lug of the tube being in section and resting upon the spring and in the slot of the outer case; and Fig. 4 is a side elevation of a portion of the upper end of the outer case or holder to show the spring-receiving recess therein.

The spindle a , having a sleeve-whirl, b , and the outer case or holder, d , rail e , and nut f , are and may be all as usual, except that the said outer case or holder near its upper end 50 is cut out to form a recess, c , (see Fig. 4,) in which is placed the supporting and locking

spring g , as shown in Fig. 3, after the lug h cast or fixed to the bearing-tube m has been placed in the said recess, the slot 2 leading from the recess c to the top of the tube affording passage for the lug h into the said recess c . The end 3 of the spring g enters the slot 2, which retains the spring in such position that the lug h bears on the position 4 of the spring. The lower end of the tube m does not bottom in 60 the case or holder; but the entire weight of the tube and the spindle and its load are transferred through the lug h upon the spring g ; and when the lug rests on the spring, as in Fig. 3, it will be seen that the tube is not 65 only supported in such manner that it may yield slightly vertically, but that the rotation of the tube with the spindle is checked.

The outer case or holder is surrounded at its upper end with a thin collar, n , which, besides serving to keep the spring in the recess c , also serves as a shield to prevent oil escaping from the tube being thrown against the interior of the whirl, the said collar, removable from the said outer case, being extended 75 above the top of the case and tube, as best shown in Figs. 1 and 3.

The spindle above the top of the case is surrounded by a washer, p , (shown as of conical shape,) the lower end of the washer terminating below the top of the collar n , the said washer preventing any oil following up the spindle above the tube m from being thrown by centrifugal force against the whirl, but compelling such oil to be thrown against the 85 inner side of the said collar, to be again returned by gravity into the tube and case or holder.

I have shown but one spring and lug; but more may be employed, if desired, with spindles having heavy bobbins.

In operation it has not been found necessary to give the bearing-tube any lateral play in the outer case or holder, the fit between the same being made only free enough to permit of 95 such vertical movement as may be permitted by the action of the spring g , and at the same time enable the ready removal of the bearing-tube.

The bearing-tube is turned smaller at its 100 lower extremity, to avoid any possibility of its binding in the supporting-tube through pos-

possible inaccuracies of workmanship, and the tube at its outer side is provided with a groove, 5, (see Fig. 1,) to enable the oil passing up over the tube to return into the oil-chamber 6.

5 I claim—

1. The outer case or holder, having a recess, as *c*, cut into it at one side thereof, and the spring therein, combined with the bearing-tube having a lug at one side to enter said recess and rest on the said spring, substantially as described.

2. The outer case or holder, having a recess, *c*, near its upper end, and slotted, as at 2, and the spring *g*, shaped as shown, one end, 3, of the spring entering the slot 2 and having an

arm, 4, combined with the bearing-tube having a lug, *h*, to rest on the said spring within the said recess, to operate substantially as described.

3. The outer case or holder, recessed at 2, and the spring *g* and bearing-tube having a lug, combined with the collar to retain the spring in the said recess, substantially as described.

In testimony whereof I have signed my name to this specification in the presence of two subscribing witnesses.

JOHN T. MEATS.
